UNITED STATES PATENT OFFICE.

FREDERICK L. FEISTHAMEL, OF LOS ANGELES, CALIFORNIA, ASSIGNOR TO JOHN F. PENROSE, OF NEW YORK, N. Y.

PIPE JOINT.

Application filed January 14, 1925. Serial No. 2,381.

This invention relates to an improved type of pipe joint, and is particularly directed to a packed screw-threaded joint especially adaptable for use in connection with well

5 casing, rotary drill-pipe, or well tubing.

A string of well casing, which consists of lengths of casing screw-threaded together, may in many instances be at least four thousand feet in length, and as a casing 10 string of such length may weigh approximately forty tons, it will be evident that the screw-threads joining the several lengths are subjected to heavy stripping strains.

It will also be understood that during the 15 drilling of a well the casing is subjected to vibrations having an excessive crystallizing effect on such joints as are not tight. Further, well casings are subjected to heavy static pressure of the fluid column usually 20 contained therein, this fluid having a contained sand content which tends to work in between the screw-threads of the joints and cause such wear as to render the joints more or less inefficient and more liable to crystallization.

In the rotary system of drilling, mud-laden fluid is forced down the drill stem by the slush pump under a pump pressure sometimes as high as 800 pounds per square 30 inch, such fluid discharging at the bottom of the well bore and returning to the ground surface through the well casing, and under these conditions and considering the heavy vibrations due to rotary drilling, it will be 35 evident that even a slight looseness of any of the screw-threaded joints in either the casing string or the drill-pipe string will be very liable to be the cause of a parting of the string containing such loose joint.

40 It will thus become apparent that it is desirable to prevent any sand-laden fluid from entering between the screw-threads of the several joints.

In view of the above, it is the object of the 45 present invention to provide a screw-threaded pipe joint having provisions for packing such joint against entrance of such fluids.

Various other objects and advantages will 50 be more fully apparent from the following description of the accompanying drawings, which form a part of this disclosure, and which illustrate a preferred form of embodiment of the invention.

Of the drawings:

55 Fig. 1 is a vertical section through the co-

engaging ends of two pipe sections constituting a packed screw-threaded joint constructed in accordance with the present invention.

Fig. 2 is an enlarged partial section illustrating a modified form of joint, the component members being partly tightened.

Fig. 3 is a view similar to Fig. 2, showing the component members fully tightened.

Fig. 4 is a fragmentary section showing a modified form of outer packing, the component members of the joint being only partly tightened.

Fig. 5 is a view similar to Fig. 4, showing the component members fully tightened; and

Fig. 6 is an elevation of a pipe coupling and adjacent pipe ends constituting component parts of pipe joints embodying the principles of the present invention.

In the drawings, there is shown the threaded ends of two adjacent casing sections 1 and 2 formed to provide what is usually referred to as an inserted joint, that is, the one section is screwed directly into the adjacent section without the use of an intervening collar, while in Fig. 6, there is shown the two adjacent casing sections 1^b and 2^b jointed by an intermediate coupling 3, the principles of the present invention being equally applicable in either case.

In Fig. 1, the upper end of the lower casing section 1 has a hub portion providing a shoulder 5 for engagement by an elevator, as is usually employed in oil field practice for raising or lowering a string of well casing, said end being internally screw-threaded and provided, at the base of said screw-threads, with a concentric packing groove or recess 6 in which is positioned a packing ring 7 constructed of compressible material and angularly split as indicated at 8, to facilitate an easy insertion thereof into said groove. This packing ring may be constructed of any one of a wide range of packing material, for instance, it may be of fiber, 90 rubber, composition, or one of the many types of hydraulic packing, or it may be of relatively soft metal such as lead, babbitt, or copper.

The lower end of the adjacent casing section 2 is screw-threaded for engagement into the section 1, said coengaging threads being preferably standard tapered pipe threads. The threads on the section 2 terminate short of the lower end of said section and the pe-

ipheral wall surface 9 of this unthreaded end portion is slightly tapered longitudinally so that when, in the tightening of the joint, said tapered surface engages the packing ring 7, said ring will be radially compressed to form a fluid tight joint, it being preferably intended that when the joint is fully tightened, the terminal end of the tapered surface 9 will be translated at least 10 to the lower edge of the packing ring so that said ring will be entirely enclosed within its groove, as shown in Fig. 1.

In Figs. 2 and 3 there is shown a joint having at its inner end the same packing structure as above described and in which the packing ring 7^a in the groove or recess 6^a of the casing section 1^a is radially compressed by engagement therewith of the tapered surface 9^a of the casing section 2^a. 20 At the upper end of the section 2^a, there is formed an internal concentric recess 10 having a vertical side wall, the lower portion of said wall gradually curving inwardly to provide a cam surface 11, and 25 the casing section 1^a is provided above the base of its threads, with a shoulder 12, the outer diameter of which is slightly less than the major diameter of the recess 10 so that said shoulder may enter said recess.

30 Within the recess 10 there is positioned a ring 13 of packing material which may be of the same or of a different material than is the packing ring 7. When this ring 13 is constructed of a material which will normally retain its ring contour, it will preferably be of rectangular contour in cross-section, as shown in Fig. 3, and in assembling the joint said ring may be first placed within the recess 10 or it may be slipped 35 over the threaded end of the section 2^a, before the section 2^a is inserted into the section 1^a. From an examination of Figs. 2 and 3, it will be clear that as the sections are screwed together the terminal tapered 40 surface 9^a will engage the packing ring 7^a and the shoulder or abutment 12 will engage the upper surface of the packing ring 13, as shown in Fig. 2, and that as the joint is 45 further tightened the packing ring 7^a will be radially compressed, as previously explained, and the packing ring 13 will bodily be driven downwardly, its lower portion being turned inwardly by the cam surface 11 and radially compressed into the thread 50 grooves of the casing section 2^a, as shown in 55 Fig. 3, thus forming a fluid tight joint.

In Figs. 4 and 5, I have shown a pliable packing 13^a in place of the packing ring 13, and which may be any suitable type of rope 60 packing material, and in the use of such pliable packing it will be preferable that the sections are first assembled and partly screwed together, as shown in Fig. 4, and

the packing then placed within the recess 10, a subsequent tightening of the joint causing the packing 13^a to be radially compressed into the adjacent thread grooves of the section 2^a.

It will be noted that the terminal ends of both the upper casing sections 2 and 2^a are tapered inwardly and rounded so as to have no sharp corners which would tend to catch upon the lower packing ring.

While the specific forms of embodiment herein illustrated and described are fully capable of fulfilling all of the objects primarily stated, it is to be understood that I do not wish to limit the invention in this regard, for it is susceptible of embodiment in various other forms, all coming within the scope of the following claims.

I claim as my invention:

1. A rigid pipe joint comprising: a member having an internally screw-threaded end; a second member having an externally screw-threaded end for engagement into said first member; and a compressible packing ring interposed between opposed unthreaded peripheral surfaces of said members, one of said surfaces being longitudinally angled to cause radial compression of said ring during relative joint tightening translation of said members.

2. A rigid pipe joint comprising: a member having an internally screw-threaded end; a second member having an externally screw-threaded end for engagement into said first member, and compressible packing rings positioned respectively at opposite ends of the coengaging screw-threads between opposed peripheral surfaces of said members, said surfaces being formed to cause radial compression of said rings during relative joint tightening translation of said members to seal the opposite ends of the screw-threads.

3. A rigid pipe joint comprising: a member having an internally screw-threaded end and provided with a packing groove beyond the inner end of its threads; a compressible packing ring within said groove; a second member having an externally screw-threaded end and provided with a smooth longitudinally angled peripheral wall beyond said threads adapted to engage and radially compress said ring during relative joint tightening translation of the members; the extreme end of the second member being tapered or rounded to prevent said second member catching upon the ring during assembling of the members.

In testimony whereof, I have hereunto set my hand at Los Angeles, California, this 6th day of January, 1925.

FREDERICK L. FEISTHAMEL.
